1 Claim

ABSTRACT OF THE DISCLOSURE

Fluid is sparged into a highly turbulent zone of a rolling bed of particulate solids in a horizontal revolving drum with minimum drag on the bed by permitting forces acting in the bed to move the sparger in a substantially vertical path, intersecting at a substantial angle the nodal area between particles which are moving upward and particles which are flowing downward.

SUMMARY OF INVENTION

In the manufacture of fertilizer it is common practice to employ a horizontal revolving drum apparatus for the mixing, agglomerating and carrying out reactions of fluids with particulate solids. The drum is usually arranged in a substantially horizontal position, slightly inclined, and is revolved by means of an external drive through a ring gear which surrounds the periphery of the drum. Considerable power is consumed in revolving a drum containing a bed of particulate solids. This is easily demonstrated by filling an oil drum approximately one-third full of moist sand, laying it on its side, and rolling it. It will be found to require considerable work to roll a drum partly filled with moist sand, whereas a drum completely filled with sand rolls quite easily on a level surface. The reason is, of course, that a partly filled drum must continuously lift a mass of particulate solids centered below the axis in order to turn, whereas in the filled drum the mass is centered along the axis and is not lifted. The solids which are lifted consume the power, and the energy absorbed by lifting is then dissipated as the particles roll downward from the top of the bed. With all of the energy expended in rotating the drum going into the rolling bed of particles, it is apparent that the bed is capable of expanding this energy intermittently by exerting rather large forces over a substantial distance. In carrying out reactions in a rolling bed, as for example in ammoniation of particles of calcium superphosphate, it is a preferred practice to submerge a perforated pipe or other form of sparger by means of a strong supporting structure within the bed in a turbulent zone, usually as near as possible to a nodal area separating the particles which are moving upward from those which are flowing downward. This type of arrangement is illustrated, for example, in U.S. Patents 2,741,545 and 2,945,747. In spite of the most careful positioning of the sparger, it is found that considerable force is exerted against the sparger and its mountings from time to time and very often a sparger is suddenly broken or wrenched loose from its mountings without previous indication of potential trouble. The forces exerted against the sparger result from variations in the flow paths of the particles. This may be occasioned by the clumping of some particles together or by variations in the amount of liquid in the bed at different places. Or, as often happens, the amount of force on the sparger continuously increases because of the formation of solid deposits upon the sparger itself. It is a common practice to reverse the direction of rotation of the drum for short

2

periods of time in order to break off the solid deposits clinging to the sparger pipe.

It has now been discovered that the drag of the sparger against the moving bed can be reduced to a minimum by mounting the sparger in such a way that it moves in response to forces exerted by the particles in the bed in a substantially vertical path, which intersects at a substantial angle the nodal area between particles which are moving upward and particles which are flowing downward. In both FIGURE 1 and FIGURE 2 of the drawing are illustrated mountings of a sparger pipe so that it moves through a vertical path CD which intersects the nodal surface AB which separates upward flowing particles from downward flowing particles. By permitting the sparger pipe to be moved up or down by the forces exerted within the bed, there is a tendency for the upward and downward forces exerted against the sparger to be balanced out so that the sparger remains at all times substantially in the nodal surface, moving up and down with variations in the flow pattern of particles. The following examples are presented for illustrative purposes.

Example I

In a pilot plant size granulating drum having a diameter of about four feet was placed a quantity of superphosphate which was moistened with phosphoric acid and was continuously ammoniated by means of a sparger made of perforated on-quarter inch pipe mounted longitudinally on two arms, one attached at each end in the manner shown in the diagram of FIGURE 1. The moving bed of solids was about four inches deep. Ammonia was fed through the perforated sparged pipe while the drum was rotated at a peripheral velocity of about 150 feet per minute. The arm was observed to move up and down over a very short path rather slowly and unevenly without exerting substantial force on the support on which the arms were pivoted. When ammoniation was begun and the temperature and moisture content in the bed began to change, it was noticed that the sparger appeared to change its position in the bed, indicating that the forces being exerted from opposite sides of the sparger pipe had undergone a change. From this it was concluded that if the sparger had been placed in a fixed position, the substantial changes in moisture content in the bed would have caused an increase in the drag of the sparger. Continuous operation over a period of about six hours successfully demonstrated that the method of sparging resulted in minimizing forces exerted against the sparger pipe as well as formation of solid deposits on the pipe. The apparatus was shut down and started up the following day without problems, was operated again for six hours, and this was again repeated on the next day without difficulty in either start-up or continuous operation.

Example II

In a fertilizer manufacturing process, a horizontal rotating drum is employed, which is approximately forty-five feet in length, ten feet in diameter and has a horizontal slope of about 17 inches from the feed end to the discharge end. In this drum, approximately one ton of particulate solids are treated at one time. In ammoniation of superphosphate, a perforated sparger pipe distributes liquid ammonia from a supply tank into the bed of solids. The sparger pipe is mounted with a four-bar arrangement at each end as illustrated in FIGURE 2 of the drawing. The four-bar mounting is made of corrosion-resistant materials. With the minimizing of forces exerted against the mounting, the parts need not be of heavy construction.

The four-bar linkage for obtaining desired types of motion is well known to mechanical engineers. (See for

example C. M. Ham et al., "Mechanics of Machinery," fourth edition, pages 19 to 22, McGraw-Hill, 1958.) Preferably the movable arms, customarily called the crank, rocker and connecting rod, may be adjusted in length with respect to each other in order to obtain a path CD, as shown in the drawing, which has the desired shape. As the volume of the bed of particulate solids, their specific gravity, moisture content and so forth are varied, the nodal area AB separating upward moving from downward moving particles will change in curvature and position and the forces exerted by moving particles will change in magnitude. It is therefore desirable to be able to make adjustments in the positions of pivots so as to obtain the type of path of sparger movement which will minimize oscillations of sparger and substantially eliminate drag. This may be conveniently accomplished by using support arms which contain a number of holes, so that pivot bolts can be changed in their positions. This type of mounting for the sparger is very economical with respect to space, leaving considerable room at the lower portion of the rolling bed of particulate solids. It may be desirable to have this area clear of obstructions for the purpose of reactor cleaning or addition of liquids to the top of the moving bed with a spray arrangement.

It happens occasionally that a solid deposit forms on the inside wall of a granulating drum and breaks loose, falling on the bed. Large chunks of solids which get into the moving bed in this way are often responsible for damage to submerged spargers. The apparatus shown in FIGURE 2 is found to move very quickly in response to forces exerted by large chunks of material in the bed, relocating the sparger after the chunks have passed by, with no damage to the apparatus. This apparatus may also be used conveniently in a drum equipped with flights attached to the wall, the sparger being lifted out of the way as each flight passes under it and immediately repositioning itself thereafter.

It is necessary for the vertical path of sparger movement to intersect the nodal area represented by cross-section AB at a substantial angle in order to prevent violent sparger movement. When the path of sparger movement almost coincides with the contour of the nodal area there is a tendency for the sparger to be alternately lifted and swept back downward so that it oscillates rapidly, resulting in loosening of mounting bolts, excessive wear and eventual fatigue of the sparger pipe or its supports. The existence of vibration with resulting fatigue

of metal parts is believed to be a cause of mechanical failures experienced with fixed spargers, in spite of efforts to mount them as rigidly as possible.

It will be understood that the limiting of the movement of the sparger pipe to a substantially vertical path may be readily accomplished by other mechanical arrangements. Whatever arrangement is used, however, it should be kept in mind that the supports for the sparger should offer as little resistance to flow of solids as possible, so that the forces which are exerted against the sparger by the moving particles are exerted primarily against the sparger pipe itself. In view of the fact that the method of sparging results in a cancellation of forces, the support structure may be quite thin in cross-section and light in weight. In operation it is found that the sparger moves up and down irregularly, indicating that it is adjusting itself to a changing balance of forces and these variations are believed to account for the lack of large deposits of solids on the sparger pipe. It appears that the irregular variation of forces in the bed and in the position of the sparger exert a scrubbing action which keeps the sparger pipe substantially free of solid deposits which would otherwise exert drag on the bed. Furthermore, since the sparger does not press against the bed as fixed spargers do, deposits do not tend to accumulate on the interior wall of the rotating drum.

What is claimed is:

1. A method of sparging a fluid into a rolling bed of particulate solids comprising sparging fluid through openings in a conduit for said fluid which is flexibly mounted so that the conduit is permitted to move only in a substantially vertical path in response to forces exerted by the moving particles in the bed, said vertical path intersecting at a substantial angle the nodal area between particles being lifted upward and particles which are flowing downward.
